(57) **CLAIM**

A mobile inhaler device, as shown and described.

DESCRIPTION

FIG. 1 is a perspective view of a mobile inhaler device according to my new ornamental design;

FIG. 2 is a left side view thereof, with the right side view thereof being a mirror image thereof;

FIG. 3 is a top view thereof; and,

FIG. 4 is a front view thereof.

The bottom and rear views of the mobile inhaler device are not shown, and form no part of the claimed design.

The broken lines of the mobile inhaler device indicate environment or structure and form no part of the claimed design.
